(57) **CLAIM**

The ornamental design for a bark siding panel, as shown and described.

DESCRIPTION

FIG. 1 is a top perspective view of a bark siding panel.

FIG. 2 is a top view of the bark siding panel seen in FIG. 1.

FIG. 3 is a bottom view of the bark siding panel seen in FIG. 1.

FIG. 4 is a left side view of the bark siding panel seen in FIG. 1.

FIG. 5 is a right side view of the bark siding panel seen in FIG. 1.

FIG. 6 is a front view of the bark siding panel seen in FIG. 1; and,

FIG. 7 is a rear view of the bark siding panel seen in FIG. 1.

The broken lines shown in FIGS. 1-7 are for illustrative purposes only and form no part of the claimed design.
